CLAIM

The ornamental design for a distilled spirits glass, as shown and described.

DESCRIPTION

FIG. 1 is a side elevation view of a distilled spirits glass showing my new design;

FIG. 2 is a side elevation from another side, showing that the design is axially symmetric;

FIG. 3 is a top plan view thereof; and

FIG. 4 is a bottom plan view thereof; and,

FIG. 5 is a cross-sectional view taken along line 5—5 in FIG. 2.
